UNITED STATES PATENT OFFICE.

CHARLES A. NELSON, OF UTICA, NEW YORK, ASSIGNOR TO SAVAGE ARMS CORPORATION, A CORPORATION OF DELAWARE.

FIREARM.

Application filed August 22, 1916. Serial No. 118,227.

To all whom it may concern:

Be it known that I, CHARLES A. NELSON, a citizen of the United States, residing at Utica, Oneida County, New York, have invented the following described Improvements in Firearms.

The invention is an improvement in shoulder fire arms and relates more particularly to the structure and relation of the parts which control the breech bolt and the hammer or striker and their compact organization in the breech part of the gun, the object being to reduce the number of parts and simplify the construction, and especially to reduce the lengthwise dimension of the breech mechanism, thereby reducing the weight and improving the balance of the arm. The invention thus consists in the principles of assemblage and cooperation of the gear frame, sear, trigger and safety mechanism as hereinafter explained and more particularly identified by the appended claims.

In the accompanying drawings—

Fig. 1 is a substantially central longitudinal section through the breech portion of a gun embodying my invention, the safety mechanism being shown in elevation and at "fire;"

Fig. 2 is a top plan of Fig. 1, the safety being shown in dotted lines;

Fig. 3 is a view similar to a portion of Fig. 1 but showing the safety bar in locking position;

Fig. 4 is a section on the line IV—IV of Fig. 3;

Fig. 5 is a section on the line V—V of Fig. 1;

Fig. 6 is an edge view, detached, of the lug wall 11.

Fig. 7 is a perspective view of the safety bar;

Fig. 8 is a view similar to Fig. 1 showing a variant form of the safety mechanism;

Fig. 9 is a plan view of the parts of Fig. 8, with the safety in dotted lines;

Fig. 10 is a view similar to Fig. 8 but showing the safety in locked or "safe" position; and

Fig. 11 is a transverse section on the line XI—XI of Fig. 8.

In these figures the invention is illustrated as incorporated in and forming a part of a magazine rifle of well-known type in which the bolt 1 is rotatable and movable

endwise; the rotary movement serving to lock and unlock it and the endwise movement to eject the spent shell, reload the chamber and cock the firing pin or striker 2. For imparting these movements to the breech bolt the latter is provided with a side lever 3 guided in a transverse slot in the breech casing 4 when rotating the breech bolt and in a longitudinal slot when being pulled back or pushed forward. During the return of the bolt to its forward and locked position, the striker is arrested by engagement of its lug 5 with the nose or upwardly extending rear end of the sear 6 and upon the completion of the forward bolt motion the striker spring is put under compression and the gun is ready to fire. The magazine disposed in the breech case, below the bolt, is adapted to contain the supply of cartridges laterally superposed and subject to upward movement into the path of the bolt by a spring-pressed follower 7 of usual design. The bottom wall 8, constituting a floor plate to the magazine chamber, is removable together with the spring and follower, by sliding it rearwardly and off of the ledges 9, to which ledges it is normally confined by the spring-pressed bolt 10 presently referred to. The gun stock is applied to the rear of the breech frame so as to provide a space in rear of the magazine wherein are compactly confined the combination of members to which my invention pertains.

Referring first to Figs. 1 to 6, the members alluded to include a frame member 11 constituting in effect a depending lug or wall which is rigidly secured by screws to the under part of the receiver as indicated in Fig. 5. This transverse wall or lug is disposed immediately in rear of the magazine which it backs up and supports against rearward thrust, and also forms a connection between the receiver and the lower frame member and trigger guard 12, the latter being bolted to the lower end of the lug 11 as also shown in Fig. 5. The connection between the receiver and trigger guard at this point forms a substantial reinforcement to the framework of the gun without material increase of weight as will be evident. At its upper end the lug 11 is recessed to accommodate the pivoted end of the sear 6 and part of the trigger within the sear and it is also bored to form the sockets for the sear spring 13 and for the locking bolt 10.

and its spring. By thus recessing the lug it is plain that the sear—itself of appropriate length—can occupy a position further forward than would otherwise be the case if the lug were not provided with an opening. The sear is fulcrumed on a cross pin 14 in the lug opening as indicated in the drawings, and its rear upturned nose projects through a slot in the receiver where it is situate in the path of the cocking lug 5 on the striker 2. The trigger 15 is pivoted on a short cross-pin 16 carried by the sear and bears by its heel 17 against an abutment part 18 of the receiver, the point of bearing being in the rear of the sear pivot so that whenever the trigger is pulled it rocks on its said abutment and thereby acts through its pivot 16 to pull the sear downwardly so as to withdraw its nose from the striker lug 5. This movement of sear and trigger is made against the resistance of the sear spring 13 which spring is seated in the rearwardly projecting pocket bored in the lug 11 and imparts its thrust upwardly to the sear to press the trigger heel against its said abutment and thereby to swing the trigger forward until its forward extension 19 strikes a stop of some sort, in the present case the fulcrum pin 14 of the sear. The engagement of the arm 19 with the pin determines the extent of the said spring-urged movement, and holds the parts in the position indicated by Fig. 1 with the sear nose projecting into the path of the cocking lug 5 as described. The sear spring is shown as acting on the sear by contact with a concentric arc-shaped surface of the trigger thus imparting its pressure to the sear through the intervention of the latter and constituting a feature of compactness, as will be evident. Obviously however, the spring could act directly on the sear if required or indirectly on some other part with the same effect. It will be observed in passing that by compounding the pivot of the trigger upon that of the sear, as by pivoting the former upon the latter and by disposing the forward part of the sear in the recess of the lug, these parts are brought into a minimum compass. The rear side of the cocking lug 5 is bevelled as customary, to ride over the sear, as the breech bolt is retracted. Moreover, the forward side of the sear nose serves to limit this rearward motion and by pulling the trigger to depress the sear when the bolt is retracted it can be further withdrawn and removed from the receiver.

The magazine bolt 10 above referred to is confined in its bore in the lower part of the lug 11 by a small cross-pin engaging its slabbed side within the bore. The end of the bolt protrudes normally into a recess in the lower frame member 12 where it obstructs the rearward sliding of the magazine

floor plate 8. The edge of the latter however, is perforated in line with the bolt so that the pointed end of a cartridge for instance can be inserted to press the bolt upwardly and thereby unlock the plate 8 to 70 permit its removal as above described.

The safety or locking device for the improved gun is in the form of a lever or flat bar having a compound tilting and endwise movement, from its "safe" to its "fire" 75 positions. This character of motion combines effectively with the compact organization above described and permits a single part or piece of metal to lock both the breech bolt and the sear and allows the safety 80 thumb piece 20 to be disposed at the top center of the grip where it is not only conveniently operated and easily seen, but is operated by a forward thrust of the thumb to set it at "fire". The safety bar or lever 85 referred to is separately shown in Fig. 7 and it will be noted that its forward end is offset and that for convenience this offset end is included in the sectional views of Figs. 1 and 3 notwithstanding these views 90 are otherwise confined to the central section of the gun. The said bar is fulcrumed by its lengthwise slot 21 on a cross pin 22 in a fulcrum post 23 secured to the receiver. Its rear end is pivotally connected to the 95 thumb piece 20 and the latter is slidingly held on a base piece 20^a which is inclined to the axis of the gun at an angle substantially equal to the drop of the stock. The forward and upward movement of the 100 thumb piece thus shoves the safety bar bodily forward on its fulcrum pin 22 and swings its forward end downwardly, while the reverse movement of the thumb piece produces the reverse movement of the lever. 105 The forward end of the lever is provided with two locking parts or branches; one marked 24 is in the plane of the thumb-piece and sear and is adapted by the thumbing movement to shift into and out of obstructing position to the sear on which an abutment seat is provided for it, as shown. The other branch, marked 25 being the offset portion, extends upwardly alongside of the sear (Fig. 4) and through the wall of the 110 receiver where it may enter a recess 26 in the surface of the breech bolt. When engaged in this recess the breech bolt cannot be rotated to unlock it and when the bolt is moved so that the recess 26 is not in registry with the end 25 of the safety bar, the bar cannot be operated. Thus the rearward operation of the thumb piece causes upward and rearward movement of the locking ends to 115 obstruct operation of both the sear and the breech bolt while its forward operation producing forward and downward movement of the said ends releases them. Snap movement is provided for the safety bar by a spring detent 27 of obvious design carried 120 125 130

by the fulcrum post 23 and which engages one or the other of the depressions in the top of the bar to hold it in either of its extreme positions. The post 23 is formed with its shoulder 23^a to bear against the under side of the thumb piece base 20^a and is utilized as a means of securing the said base piece to the rear end of the receiver. As shown in Fig. 1 the upper end of the post extends through the said piece and the rear part of the receiver, being upset upon the latter and thereby constitutes itself and the said base piece as a rigid part of the gun frame. The said fulcrum post serves the further purpose moreover of retaining the wooden stock to the frame of the gun for which purpose its lower end is threaded and a screw 28 is used to hold the stock firmly engaged with it.

In Figs. 8 to 11 the general construction will be recognized as similar to that already described, the lug 11^a corresponding to the lug 11 of the first form, but omitting that rearward part which constitutes the socket for the sear spring. In this form the sear is fulcrumed at 30 to the receiver and the sear spring 13^a is housed in the socket in the sear itself and on the forward side of its fulcrum, thrusting downwardly on this part of the sear and upwardly against the bottom of the receiver to urge the sear to its cocking position. The trigger 15^a is pivoted as before on a cross-pin 16^a carried by the sear and is adapted to rock by its heel portions 17^a upon the receiver to swing the sear downwardly. This trigger action is made against the pressure of the sear spring which reacting restores the parts to normal position, substantially in the manner already described, and as will be evident without description. The safety bar 31 having the compound tilting and endwise movement already described in connection with the safety bar of the preceding form, and fulcrumed in the same kind of frame post 23, is provided with a part 24^a which moves into and out of obstructing position to the sear 6^a. Its extreme forward end is connected by a slot and pin to a bolt 32 which is housed and guided in the sear itself and within the sear spring 13^a and the forward and downward movement of this end of the bar, produced by forward thumbing of the thumb piece 20, withdraws the bolt 32 from the recess 26^a in the breech bolt. The opposite movements enters it in the said recess when the breech bolt is closed and the effect is otherwise the same as first described. The lug 11^a also contains the magazine bolt 10 as before and by its connection to the trigger guard reinforces the gun frame and supports the magazine.

Claims:

1. In a fire-arm of the kind described, the combination with a longitudinally movable

breech bolt carrying a striker and means for releasing the latter, of a safety bar having compound tilting and endwise movement whereby said bar obstructs operation of said bolt and striker.

2. In a fire-arm of the kind described, the combination with a rotatable and longitudinally moving breech bolt carrying a striker and means for releasing the latter, of a safety bar having compound tilting and endwise movement adapting it to obstruct operation of said bolt and striker and a thumb-piece mounted on the top center of the grip to move lengthwise of the arm and constituting the operating member for said safety bar.

3. In a fire-arm, the combination of a rotatable breech bolt and locking means therefor, including a bar pivoted intermediate of its ends and a thumb piece at one end and the opposite end being disposed for locking engagement with the breech bolt when the latter is in firing position.

4. In a fire-arm, the combination of a rotatable breech bolt and locking means therefor, including a bar pivoted intermediate of its ends, and slidable endwise in respect to its pivot into locking engagement with said breech bolt and a thumb piece for actuating said bar pivotally connected thereto.

5. In a fire-arm, the combination with a rotating and sliding breech bolt and a pivoted sear, of a thumb piece centrally disposed at the rear of the sear on the upper side of the gun stock and mounted to slide at an inclination to the axis of the fire-arm, said thumb piece being provided with a locking bar extending forward therefrom into the fire-arm substantially in the central plane thereof for locking said breech-bolt against rotation and unlocking the same and locking and unlocking said sear.

6. In a fire-arm, the combination of a rotatable breech bolt, a thumb piece at the upper side of the grip mounted to slide at an inclination to the axis of the fire-arm, said thumb piece being provided with a locking bar extending forward therefrom into the fire-arm for locking said breech bolt.

7. In a fire-arm, the combination of a rotatable breech bolt, a thumb piece at the upper side of the grip mounted to slide at an inclination to the axis of the fire-arm, and a safety bar extending forward into the fire-arm substantially in the central plane thereof and operated by said thumb piece for locking said breech bolt.

8. A safety lock for fire-arms of the sliding breech bolt type including a bar pivoted intermediate of its ends and movable endwise in respect to its pivot and in the central vertical plane of the fire-arm, a thumb piece connected to one end of said bar and a locking projection at the opposite end offset from the longitudinal plane of the thumb piece.

9. In a fire-arm, the combination of a rotatable breech bolt having a locking recess, a firing pin, mechanism for releasing the latter and a locking mechanism independent of said mechanism having a finger piece on the stock portion of the fire-arm and extending therefrom into the receiver to enter said recess to lock the bolt against rotation.
10. In a fire-arm, the combination of the bolt action and firing mechanism, a safety bar pivoted to swing in the vertical central plane of the fire-arm and having one end terminating in a thumb piece at the upper side of the grip, the other end terminating in projections adapted for joint locking engagement with the bolt action and firing mechanism.
11. In a side lever fire-arm having a rotating bolt, a safety lock including a movable bar contained within the breech case and provided with separate integral projections at its forward end respectively adapted for engagement with the bolt to prevent the rotation thereof and with the firing mechanism to lock the same and an operating thumb piece on the top of the grip connected to said bar.
12. In a fire-arm, the combination of a breech bolt, and a safety mechanism including a bar pivoted intermediate of its ends, a locking bolt pivotally connected to one end of said bar and adapted for locking engagement with the breech bolt, and a thumb piece at the opposite end of the bar.
13. In a fire-arm, the combination with a breech bolt, striker and sear of a safety mechanism including a bar adapted to prevent operation of the sear, a part of said bar lying in the vertical central longitudinal plane of the arm and a part being offset adjacent the sear and adapted to lock the breech bolt.
14. In a fire-arm, the combination of a pivoted sear, a trigger pivoted thereon, a safety bar having a thumb piece in rear of the sear and having a compound endwise and tilting movement into the path of the sear.
15. In a fire-arm, the combination of a pivotal sear, a trigger pivoted thereon, a safety bar having a thumb piece in rear of the sear mounted to slide at an inclination to the axis of the fire-arm, said bar receiving compound endwise and tilting movement from said thumb piece.
16. In a fire-arm, the combination of a breech bolt, a pivotal sear, a trigger pivoted thereon, a safety bar having a central thumb piece in rear of the sear and having parts moved thereby into locking engagement with the sear and the breech bolt respectively.
17. In a fire-arm, the combination of a breech bolt, a pivotal sear, a trigger pivoted thereon, a safety bar having a thumb piece in rear of the sear, a part of said bar being adapted to obstruct the sear and another part of said bar being laterally offset from the sear-obstructing part and adapted to lock the breech bolt.
18. In a fire-arm, the combination of a sear pivotally mounted at its forward end, an upwardly acting spring intermediate of the ends of the sear and in the rear of the pivot thereof, and a safety device having a portion below said sear and movable upwardly and rearwardly into the path of the rear swinging end of the sear.
19. In a fire-arm, the combination of the receiver having a sear fulcrumed therein at the forward end of said sear, a trigger pivotally carried on the sear and a spring acting directly on the trigger to hold the same and the sear in cocking position.
20. In a magazine fire-arm, the combination with the gun frame including the receiver, sear and trigger guard, of a single member rigidly connecting the receiver and trigger guard and constituting also a rear wall of the magazine chamber and having a rearwardly extending lug independent of said connection and presenting a socket seat for an upwardly acting spring for said sear.
21. In a magazine fire-arm, the combination with the gun frame including a receiver provided with a depending transverse walled member immediately in the rear of the magazine, a sear having its front end pivoted within a recess in said member, a sear spring carried by said member, and a lower frame member rigidly secured to said wall member.
22. In a magazine fire-arm, the combination with a gun frame including a receiver having a safety base piece secured to its rearwardly extending extremity a depending transverse wall on said receiver immediately in rear of the magazine, a lower frame member secured to said wall member and a gun stock removably attached to said last named member and the said safety base piece.
23. In a magazine fire-arm, the combination with a gun frame including a receiver and a lower frame member rigidly united by a transverse wall immediately in rear of the magazine, of a safety bar having a fulcrum post in rear of said wall and a gun stock secured to said post and to said wall.
24. In a magazine fire-arm, the combination with a gun frame including a receiver and a lower frame member rigidly united thereto by a transverse wall in rear of the magazine, of a safety bar having a thumb piece central of the gun and a fulcrum in rear of said wall, a sear and trigger centrally disposed between said fulcrum and the said wall, a portion of said safety bar being central to the gun and a part being offset and lying alongside of the sear.
25. In a fire-arm, the combination with the breech bolt, striker and cocking and re-

leasing means, of a safety bar having compound tilting and endwise movement and a spring detent cooperating with sockets in said bar to retain it in its extreme positions, 5 said sockets being disposed adjacent the pivoting point of the bar.

26. In a firearm, the combination with a 10 sliding and rotating breech bolt, the striker, and gunstock of a safety piece centrally disposed at the rear of said breech bolt and upon the upper side of the gunstock, and means projecting therefrom into the firearm and operated by said safety piece for simultaneously locking said bolt and striker.

27. In a fire-arm, the combination with a 15 breech-bolt and firing mechanism, of a safety mechanism including a member adapted to prevent operation of said firing mechanism, a part of said member lying in the vertical central longitudinal plane of the arm and 20 carrying a thumb-piece at the top of the grip thereof and a part being offset adjacent the firing mechanism to lock the breech-bolt.

In testimony whereof, I have signed this 25 specification.

CHARLES A. NELSON.
